ILLINOIS

APPARATUS FOR POURING MOLTEN METAL

Application filed June 27, 1928. Serial No. 288,621.

Our invention relates to apparatus for pouring molten metal into molds and among its objects are to permit more efficient handling of the metal and to eliminate the introduction of oxides, drosses and the like into the mold. The apparatus is particularly adapted to the casting of molten zinc into slabs suitable for rolling into sheets and strips but is not confined to the casting of zinc.

5 An illustrative embodiment of our invention is shown in the accompanying drawings in which Fig. 1 is a sectional elevation of the apparatus showing the same immersed in a melting pot (only a portion of the latter being shown); Fig. 2 is a sectional plan view along the line 2—2 of Fig. 1; and Fig. 3 is a similar view along the line 3—3 of Fig. 1.

The molten metal 2^a is contained in a vessel 2. Our new apparatus is shown partially 10 immersed in the metal and in readiness for pouring the same into a mold 2^b. The apparatus consists of a vessel 1 constructed preferably of suitable heat resisting material such as fire clay. The vessel is divided into two 15 chambers 3 and 4 by a depending wall 5 so arranged as to leave a passage 5^a between the two chambers. Chamber 3 is open to the atmosphere while chamber 4 has no communication with the atmosphere, when filled with 20 metal, except through tube 14. The bottom of the vessel is provided with an aperture 6 fitted with a plug 7 attached to one end of a rod 7^a, the other end of which is provided with 25 suitable means for the raising or lowering of 30 such rod and plug. These means may be of 35 any suitable construction and as illustrated consist of a piston 8 reciprocating in cylinder 9 which is in communication through pipe 11 with pipe 14 for the purpose to be hereinafter 40 described. A spring 12 serves normally to push the piston and its associated rod and 45 plug in an upward direction.

Pipes 14 extend through the roof of the chamber 4 and are connected with a supply of 50 a suitable pressure medium under pressure, for instance, compressed air. For convenience of operation the pipes 14 are each united at its upper end with the end of pipe 10 which is in direct communication with the source of pressure but is provided with a suitable

valve such as a three-way valve by means of which pipes 14 may be shut off from the source of pressure or may be so shut off while at the same time being placed in communication with the atmosphere. A safety valve 16 55 is provided in pipe 10 and a pressure gauge 17 connected with the upper portion of chamber 4 is preferably provided to permit accurate control of the pressure in such chamber.

The upper portion of the cylinder 9 is provided with a communication to the atmosphere preferably by providing a connection such as pipe or pipes 11 with one or both of pipes 14, thus providing a free communication 60 with the atmosphere for chamber 9 whenever one or both of pipes 14 are in free communication with the atmosphere. A suitable trough 13 is so arranged as to receive metal rising in chamber 3 and transfer it to the mold 2^b.

65 The operation of our apparatus is as follows: The valve 15 is set in such a manner as to prevent free communication between the atmosphere and the interior of the pipe 10 and therefore also the interior of pipes 11 70 and 14 and to the upper portion of cylinder 9, thus causing the spring 12 to raise rod 7^a and plug 7. The vessel 1 is then introduced into the molten metal some of which passes 75 through opening 6 into chambers 3 and 4, care being taken not to introduce the vessel so deeply into the metal as to cause the latter to flow over the lower edge of chamber 3. The valve 15 is then adjusted in such a manner as to close the communication to the atmosphere and open communication with the source of compressed air. The compressed air will then flow through pipe 10 into pipes 80 14 and 11. The strength of the spring 12 is so adjusted that as the air pressure rises within the apparatus the spring will immediately be compressed, and opening 6 closed by plug 85 7 so as to prevent as far as possible escape of metal from chamber 4 back into vessel 2. As pressure is built up in the chamber 4 the 90 metal in such chamber will be pushed downwardly and will thus cause the metal in chamber 3 to rise and to overflow through trough 13 into mold 2^b. When the mold has been 95 filled the valve 15 is turned in such a manner 100

as to shut off the pressure without, however, permitting the interior of tubes 10, 11 and 14 to communicate with the atmosphere. If the pressure has been properly regulated the metal will not overflow from chamber 3 thus permitting the filled mold to be removed without waste of metal. When an empty mold has been placed into proper relationship with trough 13 the valve is then again placed into the position shown in Fig. 1 and the casting continued. Care has to be taken that the level of the metal in chamber 4 does not, during the casting operation, fall below the top of the passage 5^a.

15 When the level of the metal in chamber 4 has been lowered to such a degree as to make a refilling of such chamber desirable the valve 15 is so turned as to shut off the connection with the source of pressure and open a 20 connection to the atmosphere, thus interrupting the casting process permitting spring 12 to raise the plug 7 and allowing metal from the melting pot 2 to rise within the apparatus.

If it is practical to do so our apparatus 25 may be left within the melting pot at all times even during the process of melting the metal.

While we have referred to compressed air as the medium through which to exert pressure upon the surface of the metal in chamber 4, 30 it is obvious that we may use instead of compressed air any other suitable material, for instance either some other compressed gas or even solid material. If solid material be used it would form a piston in chamber 4 35 and a piston rod or rods within pipe or pipes 14.

40 Preferably all of the parts of our apparatus such as the inner walls of chambers 3 and 4, the walls of the passage 5^a, the aperture 6, the trough 13, and the rod 7^a, are made of material which will not contaminate the metal to be poured—for instance fire clay, if the apparatus is to be used for pouring zinc.

45 Although we have described a specific embodiment of our invention it is to be understood that the invention is not restricted to such particular embodiment. Various modifications thereof in detail and in the arrangement of the parts may be made by those skilled 50 in the art without departing from the invention as defined in the claims. For instance only one pipe 14 may be employed, or three or more of such pipes, or pipe 11 may be connected directly to pipe 10, and the parts 55 which come into contact with the metal may be only lined with non-contaminating material instead of being constructed entirely of such material.

We claim:

60 1. In an apparatus for pouring molten metals, the combination of a receiver for the molten metal suitable for immersion in a melting pot and having two chambers in communication with each other, an aperture in said receiver through which the molten

metal is admitted to said chambers when the receiver is positioned within a melting pot, a closure for said aperture at the end of a rod extending through the molten metal to a point outside said receiver, mechanism for positively actuating said rod and therefore said closure, and a source of pressure communicating with one of said chambers and operative to force the molten metal in said chamber into the other chamber, and thence 71 into a mold.

2. In an apparatus for pouring molten metals, the combination of a receiver for the molten metal suitable for immersion in a melting pot and having two chambers in communication with each other, an aperture in said receiver through which the molten metal is admitted to said chambers when the receiver is positioned within a melting pot, a closure for said aperture at the end of a rod 80 extending through the molten metal to a point outside said receiver, a source of pressure communicating with one of said chambers and operative to force the molten metal in said chamber into the other chamber, and thence 85 into a mold and mechanism actuated by and simultaneously with the application of pressure to said metal, including a fluid operated piston to positively actuate said rod and therefore said closure to close said aperture to prevent escape of metal therethrough.

3. An apparatus such as claimed in claim 2 in which the mechanism for operating the closure comprises a cylinder, a piston movable within said cylinder, a rod connecting the piston and the closure and a spring surrounding said rod and tending normally to retract said closure from its opening.

4. In an apparatus for pouring molten metals, the combination of a receiver for the molten metal suitable for immersion in a melting pot and having two chambers in communication with each other, an aperture in said receiver through which the molten metal is admitted to said chambers when the receiver is positioned within a melting pot, a closure for the aperture, a valve controlled conduit, a conduit connecting the same to one of said chambers and forming therewith a continuous conduit, a third conduit connected with said continuous conduit and connecting the same with a cylinder, a piston within said cylinder, a rod connecting said piston with said closure and a spring surrounding the rod.
